UNITED STATES PATENT OFFICE.

ORSEMUS G. STILLMAN, OF HORNELLSVILLE, NEW YORK.

STILT.

SPECIFICATION forming part of Letters Patent No. 351,294, dated October 19, 1886.

Application filed July 31, 1886. Serial No. 209,671. (No model.)

To all whom it may concern:

Be it known that I, ORSEMUS G. STILLMAN, a citizen of the United States, residing at Hornellsburg, in the county of Steuben, State of New York, have invented certain new and useful Improvements in Stilts, of which the following is a specification, reference being had therein to the accompanying drawings.

This invention relates to boys' stilts; and the object of the invention is to provide a cheap, simple foot-rest that can be adjusted to any desired position on the pole, and which is adapted to be cast in a single piece; and the invention consists in certain features of construction hereinafter described, and particularly pointed out in the claims.

Referring to the drawings, Figure 1 is a side elevation of a stilt constructed in accordance with my invention. Fig. 2 is a central vertical section of the same. Fig. 3 is a rear end elevation of the foot-rest detached, and Fig. 4 is a perspective of the strap.

Like letters indicate like parts in all the figures of the drawings.

A represents the usual pole or standard, which, as usual, is rectangular in cross-section, and upon which is mounted the adjustable foot-rest B. The foot-rest B is formed with the bearing-surface B' for the foot, which in outline is adapted to conform to the ball of the foot. Back of the foot portion B', and cast at an angle thereto, is formed a clamping portion, B², said portion being adapted to loosely fit the pole A, and is formed by the three side walls, B³, and the rear abutting surface, B⁴, thereof.

Within the above-described clamping portion, thus forming a loosely-fitting collar, and within the abutting B³ of the foot-rest, I form a concavity, B⁵, and cast within the same a lug, B⁶, the top of which is flush with the surface of said abutment, (see Figs. 2 and 3 of the drawings,) whereby a strap, C, provided with eyelets C' C², is adapted to be entered therein and passed over and buttoned to said lug B⁶. The opposite end of the strap C is provided with the eyelet C², and is adapted to take over a button or lug, B⁷, formed on the extreme end of the foot-rest B. Within the clamp formed by the walls B³ B⁴, and below the concavity

B⁵, there is cast an internal transverse rib, B⁸, adapted to bite in the pole upon which the foot-rest is mounted.

For the purpose of strengthening the foot-rest and preventing the weight of the walker from breaking the same, I form on the under surface thereof a longitudinal rib, B⁹, extending from the abutting portion B⁴ to the outer end of said rest.

The operation of the invention is exceedingly simple, in that in order to adjust the plate or rest B at any desired height, it is only necessary to elevate the outer end thereof, which, by reason of the clamp being formed slightly larger than the pole, said rest may be moved up or down to a desired point. By releasing the outer end, the weight alone of the rest will be sufficient to retain it in the position desired, as the clamping portion being formed at an angle, it, in connection with the internal rib, will cause the same to bind upon the pole, which binding is greatly augmented when the weight of the person is brought to bear upon the foot-rest.

It is apparent that the foot-rest B may be set at a convenient height for mounting, and after mounting the walker may, by turning and lifting the outside of his foot at the same time, elevate said rest to a desired height and bind the same at that point by simply bearing his weight thereon. By a similar operation the companion foot-rest may be elevated. Again, if desired, the rest may be lowered to any desired position in both instances, the weight of the walker being sufficient to sink the rib B⁸ a sufficient distance in the pole to cause the rest to be held firmly in position.

From the above description it will be seen that I provide a foot-rest of a single piece, complete in all its details, that can be readily adjusted to any desired position, that is strong, durable, and that can be manufactured at a very slight cost.

Having thus described my invention, what I claim, and desire to secure by Letters Patent, is—

1. A foot-rest for stilts comprising a foot-bearing portion, a clamping portion arranged at its rear end, a button or lug within said clamping portion, and a button or lug formed

at the outer end of said rest, said button or lugs being adapted to retain a strap, substantially as specified.

2. The foot-rest B, having the bearing portion B', the clamping portion B³ B⁴, the longitudinal rib B⁵, the transverse internal rib, B⁶, and the buttons B⁶ B⁷, substantially as specified.

3. The combination of the foot-rest B, having the bearing portion B', the rib B⁵, clamp-

ing portion B³ B⁴, the internal transverse rib, B⁸, the concavity B⁹, and the lugs or buttons B⁶ B⁷, adapted to receive and retain a strap with the pole A, substantially as specified.

In testimony whereof I affix my signature in presence of two witnesses:

ORSEMEUS G. STILLMAN.

Witnesses:
